Ward, Crosby and Smith

UNITED STATES PATENT OFFICE.

LOUIS S. SCHER, OF NEW YORK, N. Y.

ACOUSTIC DEVICE.

Application filed November 2, 1923. Serial No. 672,241.

To all whom it may concern:

Be it known that LOUIS S. SCHER, a citizen of the United States, and resident of borough of Bronx, New York city, county of Bronx, State of New York, have invented certain new and useful Improvements in Acoustic Devices, of which the following is a specification.

The invention relates to improvements in acoustic devices whereby sound waves may effectively be collected, intensified and transmitted to a desired point, and more particularly to ear trumpets for aiding partially deaf persons to hear more distinctly, or for enabling persons of normal hearing to hear more clearly, sounds coming from a somewhat distant point as at the opera or the theatre.

An object of the invention is the provision of improved devices which may be readily fitted to the ear or ears of the user, which will be comparatively inconspicuous and unobjectionable in appearance, which will collect sound waves, intensify and transmit the same effectively to the ear with faithful reproduction of the quality of the sound received, and which will be comparatively inexpensive and simple in construction. Another object is the provision of such devices in which no use is made or required of vibrating diaphragms, electricity or electromagnetic means. Another object consists in the provision of an improved system or chain of chambers or passages designed to effectively collect, and intensify and transmit sound waves, truly and without loss of quality to a desired point, regardless of whether or not such waves are transmitted directly into the ear of the user. Other objects of the invention consist in the provision of improved combinations of elements and details of construction, all as will be more fully described hereinafter in the following specification, and be particularly pointed out in the appended claims.

Devices intended to aid hearing comprise those which operate mechanically, such as the well-known ear trumpet and the like, and those in which the received sound waves cause a micro-phone to vary the flow of an electric current through a conductor which operates a telephone-receiver attached to the ear. In such electrical devices a battery

must be carried in a pocket of the user, and this battery must be renewed from time to time after various periods of service. By my invention devices are provided which may be used on or removed from the ears in much the same simple manner as spectacles are positioned for use or removed in the case of a person whose vision needs aid, without the use of a battery or connections extending from the body or pocket of the user to the head. Existing mechanical devices, that is devices in aid of hearing which do not employ electricity, are generally cumbersome, and difficulty has been experienced in this class of instruments in transmitting intensified sounds without loss of quality because, for example, of the resonance of the parts, or the production of undesired sounds due to the rates of vibration natural to the parts.

In the preferred construction I provide members which may readily be clipped to the ears of the user and which will fit snugly against the ear with short tubes extending into connection with the auditory canals of the ears. These members each comprise a series or chain of chambers or passages so arranged as effectively to collect, intensify and transmit sound vibrations to the auditory canal of the ear. The chambers or passages referred to are so designed and arranged that the natural rates of vibration of their enclosed air columns will be of extremely high pitch. These air columns will not be set into vibration by the sound waves ordinarily received by the system, sufficiently to sound their own individual notes, because of the insufficient energy of the received waves. In case, however, sound vibrations of high frequency, corresponding to the natural rate of vibration of one of the chambers of the system, are received, the air in this chamber may, because of the principle of resonance, sound its own note sufficiently to reinforce to some extent the note received. This, however, will only be in the case of high pitched notes. Also, the various chambers of the system will each have a different natural high pitch rate of vibration, so that various notes of high pitch, and their harmonics, may thus be reinforced, if received. This seems to improve the quality of the sound received in such cases, and

to round out various tones of musical selections received, while not interfering with the fidelity of reproduction of the ordinary conversational tones. This is in contradistinction to various prior known devices having low-pitched resonance.

Generally speaking, the device employs a series of connected chambers or passages of gradually diminishing cross-sectional dimensions which are similar to open ended pipes of short length, these chambers or passages conveniently and preferably being arranged one within the other so as to bring the whole system into a small compass.

15 In order that the invention may be more clearly understood attention is hereby directed to the accompanying drawings forming part of this application, and illustrating one embodiment of the invention. In the 20 drawings—

Fig. 1 represents a horizontal section taken through one of the devices applied to an ear of the user, this section being taken on line 1—1 of Fig. 2;

25 Fig. 2 is a vertical section taken on line 2—2 of Fig. 1;

Fig. 3 is an outside view of the device, and

Fig. 4 is an inner side view.

30 It will be understood that the devices may be supplied in pairs, one to be worn on each ear, or a single one may, of course, be used, when the user is deaf in one ear only. In the drawings a single 35 device only is shown. The direction of sound may better be ascertained when both are used.

Referring to the drawings, the device comprises an outer or sound receiving chamber 1, preferably having a flat side 2 adapted to fit snugly against the outer surface of the ear of the user. Chamber 1 is provided with a mouth 3 which preferably is comparatively wide. Opposite to the flat inner side 2 of the chamber, there is an inclined and smoothly curved surface 4 which extends rearwardly from mouth 3 and curves around at the rear, as is indicated at 5, to join the rear end of the flat side 2. The outside 4 is curved transversely to join the side edges of the flat side 2.

The inner side 2 of the chamber is preferably provided with side edges 6, 6, which slant inwardly somewhat as they extend back from the mouth of the chamber, these side edges preferably being joined at the rear by the somewhat curved rear edge 7. The top or outer portion 4 of the chamber is, of course, shaped to join the bottom 2 about the edges thereof. Preferably all the walls of the chamber 1, or all of the walls except the side 2 thereof, are formed of celluloid, or the like transparent material, so as to be inconspicuous in appearance.

It will be noted that chamber 1 is com-

paratively short, that is, its dimension rearwards from the mouth 3 is comparatively short, and also that the mouth 3 is comparatively wide, relatively to the length of chamber 1, considering the width of the mouth as the distance between the ends of side edges 6, as shown in Fig. 3, and the height of the mouth as the distance between the front edges of bottom 2 and top 4, Fig. 1.

Within chamber 1 there is provided an enclosing structure 8 which is mounted upon the inside surface of bottom 2 of the outer chamber. This may conveniently be formed of thin sheet metal and comprises outer portion 9 which extends forwardly to a point adjacent the mouth 3 of the outer chamber, then curves towards bottom 2, as is indicated at 9¹, and then extends rearwardly, to lie against the inside surface of bottom 2 of the outer chamber, as is indicated at 10. The outer and inner portions 9 and 10 are connected by top and bottom side portions 11, 11. Communication is had between enclosure or chamber 8 and the outer chamber 1 by means of a comparatively long narrow slit or opening 12 at the rear of chamber 8, and a short distance forward from the rear curved surface 5 of chamber 1.

In the form of construction shown in the drawings a third chamber or link in the acoustic series is provided by a member 13, which extends rearwardly within chamber 8 from a mouth 14 a short distance to the rear of the closed front surface 9¹ of chamber 8. This chamber 13 comprises a top portion 13¹ and side portions 13², (Fig. 2), and extends rearwardly a convenient distance, which, as shown in the drawings, may be about half the length of chamber 8, after which it curves inwardly as shown at 15 and merges with the short tube 16 which extends out through suitable openings in portion 2 of the outer chamber and portion 10 of chamber 8. The side walls 13² of chamber 13 preferably are inclined, as shown in Fig. 2, for a distance back from mouth 14, so as to make mouth 14 as long as possible, the inclination of these side walls 13² gradually diminishing as they go back from the mouth until they are at right angles to side 13¹ opposite the opening into tube 16. Tube 16 is preferably inclined somewhat forwardly, as shown in Fig. 1, to fit more or less closely against the surface of the recess of the ear, known as the concha, 17. When so positioned the end of tube 16 preferably abuts against the flesh surrounding the outer end of the auditory canal 18 of the ear.

There is provided, in the form of construction shown in the drawings, a lip 20, which forms a continuation of the tube 16, and extends into the interior of chamber 13. This lip serves as a reflecting surface to assist in directing the sound waves which are set up in chamber 13 into tube 16. Lip 20 may

be a portion of bottom plate 10 of chamber 8 and may conveniently be stamped up from bottom plate 10.

Preferably tube 16 is divided into a number of parallel passages by small division plates 19 extending forwardly or outwardly somewhat from the inner end of the tube.

Means for detachably securing the device in position upon the ear are provided which 10 may consist of a pair of curved springy wire members 21, 21, which are secured at the rear to the inner side 2 of the chamber 1, as is indicated at 22, these wire clips then curving forwardly and outwardly. When 15 the device is to be used the short tube 16 is inserted in position, as shown in Fig. 1, and the clips 21 pressed into position to extend behind the upper and lower fleshy portions of the ear, known as the helix and 20 the lobe, and then to curve around the same and clip over them. With this construction the device is detachably anchored both front and rear, forward motion of the device being prevented by the engagement of tube 16 25 with the forward surface of the concha of the ear, while rearward movement is prevented by clips 21 passing around the upper and lower front corners of the ear.

When the device is in use sound waves 30 enter mouth 3 of the outer chamber and move rearwardly through the chamber, the density of the waves being increased and the intensity of the sound accordingly increased, because of the convergence of the 35 sides of the chamber. At the rear of the chamber the waves are reflected smoothly by the curved surface 5 behind the narrow slit 12, which forms the opening for chamber or 40 passage 8. The considerable disturbance to the rear of slot 12 is transmitted therethrough and sets the air within chamber 8 into similar vibration.

It will be seen that chamber 1 is in effect 45 an open ended pipe or air column, the natural rate of vibration of which is an octave higher than that of a closed pipe of the same length. Since the frequencies of the sound 50 waves of air columns vary practically inversely as the length, and since chamber 1 constitutes a short column which may be, for example, only about two inches long, it will be seen that the natural rate of vibration 55 of chamber 1 is high. It will be noted that the side edges 6 of chamber 1 taper inwardly with a comparatively slight inclination, the outer wall 4 preferably tapering or curving towards the flat side 2 somewhat more steeply, the shaping of these walls being adapted to reflect and compress the 60 sound waves with the greatest efficiency. The use of the comparatively small taper of edges 6 and the short length of chamber 1 results in the production at the rear of chamber 1 of a disturbance which may be considered as a band of considerable length in

comparison with its width, directly in front of the comparatively long narrow slot 12, this slot extending practically from one corner to the other of the rear edge of chamber 8.

The condensations and rarefactions of the sound waves passing through chamber 1 will, to a very considerable extent, be reflected through slot 12 in the same manner that sound waves are reflected from the end of 75 an open pipe. The length and area of opening provided by slot 12 is sufficient to enable chamber 1 to act to a considerable extent as an open-ended pipe, as stated. Furthermore, the transmission of the succeeding 80 condensations and rarefactions through such a comparatively long narrow slot I believe to be much more effective than would be the case if the sound waves were intensified by a conical trumpet and caused to pass therefrom through a comparatively small round opening at the apex thereof, as in the usual device of the character of the ear trumpet, such constructions necessitating greater 85 length of air column, and resulting in low 90 pitched resonance.

The outer wall 4 of chamber 1 is preferably domed, as indicated in the drawings, with an outward curve of greater radius adjacent the side edges 6, as is indicated at 95 23.

Upon passing through slot 12 the sound waves are permitted to expand somewhat naturally until the walls of the chamber or 100 passage 13 are encountered, the waves passing through the passage bounded by the outer wall 13¹ thereof and the wall 9 of chamber 8, and the side walls 13² and 11 of chambers 13 and 8, respectively. The advancing area of disturbance is compressed 105 somewhat further laterally in its forward passage through chamber 8 because of the fact that the side walls 11 of chamber 8 converge inwardly somewhat as they approach the front of the device (see Fig. 3). The waves are then reflected by the curved front 110 walls 9¹ of chamber 8 and pass into the mouth 14 of chamber 13, which mouth, as shown is also a comparatively long narrow slot of suitable shape to receive the waves and to enable chamber 8 to act as an open-ended column. The waves are intensified 115 somewhat further within chamber 13 since the cross-sectional dimension thereof decreases toward the tube 16. The sound waves so intensified will be transmitted 120 around the lip 20 and through the short tube 16 directly into the auditory canal 18 of the ear, tube 16 and lip 20 forming the fourth air column or chamber. The division plates 19 of this short tube 16 serve to more effectively direct the sound waves forwardly 125 through the tube.

It will thus be seen that the device comprises a series of connected chambers or passages of gradually diminishing cross-sec- 130

tional dimensions through which sound waves will be transmitted smoothly and naturally, but with an increasing compression, resulting in a corresponding increase of intensity. It will also be noted that these connected chambers are all short in comparison with the lengths of the sound waves which commonly pass therethrough, and that accordingly insufficient length will be provided for the condensation and rarefaction portions of the advancing waves to get out of phase with each other as they progress through the various chambers. Further a sufficient area of opening is provided at the mouth of each chamber to enable each condensation or rarefaction approaching such opening to freely set the air within the succeeding chamber into similar vibration without interference or retardation of the advancing wave section at the opening. It will likewise be noted that the volume of air in each chamber or link of the acoustic system is quite small so that there will be slight inertia of the elastic medium to impede transmission of rapidly changing vibrations. It will also be seen that the columns of air in the various chambers or links are of different lengths, and that each of the same has a different natural frequency of high pitch, the frequency of vibration of the outer chamber 1 being the lowest of the system, so that various notes of high frequency, and their harmonics, will be reinforced somewhat, when received, by resonance, but that the comparatively low pitched sounds most commonly received will not thus be reinforced or interfered with. In the ordinary use of the device in conversation there will be no perceptible resonance or reinforcement of the sound vibrations received, due to the reception of vibrations of frequency equal or similar to the frequencies of any of the chambers of the device, since the rates of vibration natural to the various chambers of the device are higher than the rates of vibration of the usual human voice in speaking, this in contradistinction to prior devices employing longer chambers, having low-pitched resonance, in which a low roar is always found to accompany the speaking voice. It will likewise be noted that while the device in the form here shown delivers the intensified sound vibrations directly into the ear, the system described and illustrated may be used for delivering the intensified sound at another desired point. It should also be noted that the devices described may, if desired, be used in a multiple arrangement. That is, a plurality of such devices, three for example, may be arranged in a group, if desired, with their axes at angles to each other, but their sound receiving mouths faced in the same direction, and the exit connections of the devices,

such as the tubes 16 described above, adjacent to each other. The various exit tubes in this case may all be suitably curved to lead the sound waves passing therethrough into a common exit tube, leading to the ear or to another desired point. In such a case the intensity of the received sound will be increased, while maintaining the advantages of lack of low resonance qualities, etc., inherent in each individual device. 75

It should be understood that the invention is not limited strictly to the details of construction which have been particularly described, but that the invention is considered to be of considerable breadth, as is evidenced by the following claims. 80

What I claim is:

1. An aural device, comprising a sound collecting and intensifying chamber provided at the rear with a narrow elongated space towards which the walls of the chamber continuously converge, a second, substantially flat, chamber, connecting with said space through an elongated narrow opening, running parallel to said elongated space, the entrance end of said second chamber being of a less cross sectional area than the portion of said first chamber having the least cross sectional area, and means for transmitting sound waves from the interior of said second chamber to a desired point. 95

2. An acoustic device, comprising a series of more than two connected chambers opening one into the next and decreasing in cross sectional dimensions from one to another, the entrance end of each chamber being of a cross sectional area no greater than the portion of the preceding chamber of smallest cross sectional area, the first chamber having a sound receiving mouth and the last having an exit connection, said chambers constituting short open-ended pipes the pitch of each of which is high, relative to the pitch of the usual human speaking voice. 100

3. An aural device, comprising a sound receiving chamber having a comparatively wide mouth, a short length rearwardly from said mouth, and opposite walls converging from said mouth to provide a narrow elongated space at the rear and a second chamber extending away from said space and communicating therewith through a substantially straight narrow elongated slot, parallel to said elongated space, said first chamber having a curved surface for reflecting sound waves towards said slot. 115

4. An aural device, comprising a member one side of which is substantially flat and adapted to bear directly against the outer surface of the ear to the user with a short tube extending therethrough at a forwardly inclined angle to rest against the surface of the concha with its end aligned with the mouth of the auditory canal, said member having arms adapted to clip over the helix. 125 130

and lobe of the ear, said member being constructed to collect sound waves and to intensify and transmit them to said tube.

5. An ear trumpet, comprising a series of connected chambers decreasing gradually in cross sectional area, terminating in a tube leading directly into the auditory canal of the ear and divided into a plurality of longitudinal passages.

10. 6. An acoustic device, comprising a series of more than two connected chambers, comprising short open ended pipes opening one into the next and decreasing in cross sectional area from one to another, the first chamber having a sound receiving mouth and the last having an exit connection, said chambers containing air columns each having its own individual natural rate of vibration, the lengths of all of said columns 20 being different, said columns decreasing in length from the first to the last, and being so short that the natural rates of vibration thereof are greater than the usual rates of vibration of the human voice in speaking.

25. 7. An acoustic device, comprising a series of more than two connected chambers opening one into the next and decreasing in cross sectional dimensions from one to another, the second carrying the sound waves

back through the first in reverse direction 30 and the third, within the second, again reversing the direction of the transmitted waves and carrying them out through a wall of the device, said second and third chambers being substantially flat and having 35 straight elongated narrow mouths.

8. An ear trumpet comprising a chamber member having a broad face member adapted to fit snugly adjacent the human ear, said chamber member having an opening for the reception of sound waves, and a plurality of separate chambers therein adapted to increase the intensity of the sound transmitted therethrough, each of said chambers being of gradually diminishing cross section with the smaller end of one operatively connected with the larger end of the next, said larger end being of a cross sectional area no greater than that of said smaller end of the preceding chamber, and said chamber member having an opening in said broad face through which the intensified sounds are transmitted to the auditory canal of the ear.

In testimony whereof I have signed my 55 name to this specification.

LOUIS S. SCHER.
